UNITED STATES PATENT OFFICE

2,541,810

HIGH-FREQUENCY INDUCTIVE STRUCTURE

Maynard J. Columbe, Schenectady, N. Y., assignor to General Electric Company, a corporation of New York

Application August 28, 1947, Serial No. 770,985

4 Claims. (Cl. 175—359)

1

My invention relates to a high frequency inductive structure and, more particularly, to a high frequency transformer suitable for energizing filaments of electron discharge devices that operate at high potentials with respect to ground.

Many problems have been presented in the development of high potential electron devices, such as electron and X-ray defraction instruments, electron microscopes, magnetrons, etc. One problem has been the development of adequate means for energizing the filaments of electron discharge devices used in such equipment that operate at a high potential with respect to ground. In the past, several methods have been employed for heating these filaments, for example: Batteries, 60 cycle transformers and radio frequency transformers. Batteries are objectionable in that they are too bulky and have a short life which necessitates frequent replacements. The 60 cycle transformer presents severe insulation problems and it is quite bulky and requires considerable space. The radio frequency transformer has proven the most satisfactory as it can be constructed in a minimum of space and at a low cost. However, it also presents problems in insulation and construction.

Heretofore, where the primary and secondary windings of the radio frequency transformer have both been embedded in the insulating material, considerable difficulty was encountered due to the heating of the primary winding causing a breakdown of the insulation material. Voids develop and in operation the air in these voids becomes ionized and the internal corona gradually destroys the insulating material, causing losses or in some cases a complete breakdown. By eliminating the electrostatic coupling between the primary and secondary coils, the primary coil may be placed outside of the insulating material. This is accomplished by a grounded electrostatic shield, commonly known as a Faraday shield, placed between the two windings.

It is a general object of my invention to provide an improved high potential transformer.

Another object of my invention is to provide a high frequency transformer suitable for operation at high potentials above ground.

A further object is to provide an improved high frequency transformer that is simple, compact and easy to manufacture.

A further object of my invention is to provide a transformer with negligible capacitive coupling between the primary and secondary windings.

The features of my invention, which I believe to be novel, are set forth with particularity in the appended claims. My invention itself, how-

2

ever, together with further object and advantages thereof, may best be understood by reference to the following description taken in conjunction with the accompanying drawing in which Fig. 1 is a vertical view of a transformer suitably embodying the invention; Fig. 2 is a top view of the apparatus of Fig. 1; and Fig. 3 is a schematic diagram of an oscillating circuit combined with a transformer embodying my invention.

Referring now to Fig. 3, I have shown a transformer embodying my invention together with an oscillator circuit which energizes the primary winding thereof. For illustration, I have shown an oscillator circuit of the Hartley type. However, any other suitable circuit may be used. I have shown an electron discharge device 14 having an anode 15, cathode 16, control grid 17 and screen grid 18. The cathode 16 is connected to ground through the res'stor 19 which is bypassed by capacitor 20. The high potential anode supply is designated by the conventional symbol B+ and is connected to the anode 15 through a choke 21 and is bypassed to ground by capacitor 22. A screen grid dropping resistor 23 is connected between the screen grid 18 and B+. One end of a tuned circuit, comprising a capacitor 24 and an inductance 10, is connected to the anode through a blocking capacitor 25. The other end of the tuned circuit is connected to the control grid 17. The inductance 10 has a tap 27 and a portion of the winding is connected in the grid circuit to furnish feed back stabilization.

The inductance 10 also serves as a primary winding for the transformer 4. The secondary winding 6 is embedded in a block 5 of suitable insulating material. An electrostatic shield 8 is inserted between the primary winding 10 and secondary winding 6 and is connected to ground by the terminal 9. A capacitor 28 is connected across the secondary winding 6 for tuning.

Referring now to Fig. 1 for a more detailed showing of the transformer and its construction, I have shown a molded block or envelope 5 which may be of any suitable insulating material such as resinous compounds, mica, glass or the like. In the embodiment I have found that a resinous compound, such as polyethylene, has been particularly satisfactory as it has good molding qualities. The secondary winding 6 is molded into the envelope 5 and has its two ends brought out and terminated in a co-axial connector 7. The electrostatic shield 8 is also embedded in the envelope 5 and is substantially parallel to the secondary winding 6. The spacing between the secondary winding 6 and the shield 8 is dependent upon the potential that will be impressed

upon the winding 6. It is preferred that the portion of the envelope 5 between the winding 6 and the shield 8 be solid and contain no voids. The primary winding 10 shown to be helically coiled, is mounted outside of the envelope 5 by 5 the plate 11 which is held in place by spacers 14, bolts 12 and nuts 13.

The secondary winding 6 consists of a single turn of large cross-section wire for low resistance. It is easily molded in the insulating material. Preferably it is constructed by first making a loop of almost 360 degrees, the two ends being folded back toward the center of the loop then being bent back perpendicular so as to terminate in a co-axial connector. Since the electrostatic shield is flat, it is adaptable to being molded into the surface of the insulating material. The dimensioning of the winding 6 and shield 8 to occupy substantially parallel planes facilitates mounting of these elements in the solid mass of insulating material while providing a simple, inexpensive construction. The oscillator discharge device and its associated circuit components may be mounted on a transformer itself or may be placed some distance away. In the embodiment illustrated, the inductance of the oscillator circuit is used as a primary of the transformer. However, the oscillator may be used to excite the circuit of an amplifier and the primary of the transformer may then be connected in the plate circuit of the amplifier.

The coupling between the primary and secondary windings is dependent upon the adjustment of the respective windings for stable oscillator operation and suitable transfer of energy. The load (which may or may not be tuned) may be any electron tube filament, rectifier filament, cathode ray filament, electron gun filament or any other similar load which is at high potential with respect to ground.

The purpose of the electrostatic shield is to isolate the primary and secondary windings with respect to capacitive coupling so that a high voltage charge will not build up in any air space between the two. It is necessary only to insure that no air spaces exist between the electrostatic shield and the secondary winding. Since the shield is at ground potential, no corona can form between the primary and the shield. Hence, the primary may have air space which permits better cooling.

Among the advantages of the transformer constructed in accordance with my invention, are the reduction in radio frequency power losses, especially losses in the windings. Other advantages reside in the fact that this transformer is simple, takes little space and can be manufactured at low cost.

While I have illustrated and described particular embodiments of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States is:

1. A high frequency inductive device comprising a primary winding, a secondary winding inductively coupled to said primary winding, an electrostatic shield interposed between said windings, a solid mass of insulating material, said secondary winding and said electrostatic shield being

dimensioned to occupy substantially parallel planes and being embedded in physical contact with said mass, and means for physically supporting said primary winding outside said mass and in spaced relationship with respect to said secondary winding.

2. A transformer adapted to have a high potential imposed thereon comprising a primary winding, a secondary winding, an electrostatic shield interposed between said windings, said secondary winding and electrostatic shield being dimensioned to occupy substantially parallel planes, a solid mass of insulating material, said secondary winding and said electrostatic shield being embedded in physical contact with said insulating material, means for physically supporting said primary winding outside said material and adjacent to said electrostatic shield and said secondary winding, whereby said windings are inductively coupled.

3. A high frequency transformer comprising a primary winding, a secondary winding inductively coupled to said primary winding, an electrostatic shield interposed between said windings, said secondary winding and electrostatic shield being dimensioned to occupy substantially parallel planes, a block of insulating material, said secondary winding and said electrostatic shield being embedded in physical contact with said block, a portion of said block separating said secondary winding and said shield, and means for physically supporting said primary winding in air outside of said block of insulating material and in spaced position with respect to said secondary winding.

4. A high frequency transformer arrangement comprising a high voltage winding and a low voltage winding, an electrostatic shield, said shield being embedded in physical contact with a solid electrical insulating material, said low voltage winding being embedded in physical contact with said material on one side of said shield, said shield and said low voltage winding being dimensioned to occupy substantially parallel planes, means for physically positioning said high voltage winding on the other side of said shield in spaced relation and magnetic coupling arrangement with said low voltage winding and substantially physically isolated from said material.
